UNITED STATES PATENT OFFICE.

WOLFGANG GSCHWENDNER, OF CLEATON, KENTUCKY.

ACETYLENE-GAS LAMP.

1,073,980.

Specification of Letters Patent. Patented Sept. 23, 1913.

Application filed November 23, 1912. Serial No. 734,199.

To all whom it may concern:

Be it known that I, WOLFGANG GSCHWENDNER, a citizen of the United States, residing at Cleaton, in the county of Muhlenberg and State of Kentucky, have invented new and useful Improvements in Acetylene-Gas Lamps, of which the following is a specification.

This invention relates to acetylene gas lamps, the object in view being to provide a lamp of the character referred to, especially designed for the use of miners, the said lamp being accessible in all of its parts and capable of being easily and quickly put together, after being filled, and also embodying novel means for coupling the sections of the lamp together, and at the same time supporting the lamp as a whole upon the hat or helmet of the miner.

With the above and other objects in view, the invention consists in the construction, combination and arrangement of parts, as will be hereinafter more fully described, illustrated in the accompanying drawings, and pointed out in the claim hereunto appended.

In the drawings: Figure 1 is a perspective view of the complete lamp. Fig. 2 is a vertical section through the same. Fig. 3 is a top plan view thereof. Fig. 4 is a side elevation of the lamp, showing the two sections locked together. Fig. 5 is a similar view, showing the lock thrown back.

The miner's lamp contemplated in this invention comprises a bottom section 1, and a top section 2, said sections being substantially square in cross section and of approximately equal size.

The bottom section 1 forms a single compartment in itself, and is adapted to receive the carbid, said bottom section 1 being open at the top when detached from the top section, and the top section forming a closure or cover therefor. The bottom section is also provided with the outwardly projecting keepers or projections 3 at opposite sides thereof, for a purpose which will hereinafter appear.

The top section 2 is divided off interiorly to form a gas chamber 4 in the bottom thereof, the bottom of said gas chamber being perforated, as shown at 5, to admit the gas generated in the carbid holding section 1. A burner tube 6 communicates with the gas chamber referred to, and is provided with

a suitable burner tip 7, back of which is arranged a reflector 8 attached to the top section, as shown.

Projecting downward from the water compartment or chamber located directly over the gas chamber is a guide tube 9, in which is mounted the stem 10 of a valve 10', the stem of which projects up through the top wall of the upper section 2, and is provided at its upper end with a cross head 11, the ends of which are formed into hooks 12. These hooks 12 are adapted, when the stem is pushed downward, to interlock with another stationary crosshead or keeper 13 bearing a fixed relation to the top section 2. When these two cross heads are interlocked, in the manner illustrated, the valve is closed, thereby cutting off the flow of water from the water chamber into the carbid chamber. By partially revolving the stem of the valve by means of the cross head thereon, the latter may be thrown out of interlocked engagement with the fixed cross head or keeper and drawn upward, thereby allowing the water to flow through the tube into the carbid chamber, until a sufficient amount of gas has been generated for the purposes of the miner.

14 designates a plug for closing the filling aperture 15 in the top of the upper section 2.

In order to fasten the two sections of the lamp together, and at the same time provide for supporting the lamp as a whole on the miner's hat or helmet, a forked lever 15' is provided, the arms of said forked lever straddling the top section of the lamp and being pivotally connected thereto at 16. To the central portion or crown of the forked lever is attached a hat- or helmet-engaging hook 17, the point of which extends downward, said hook also acting as a handle for coupling or uncoupling the two sections of the lamp.

Pivotally connected to the oppositely lying arms of the forked lever are coupling hooks 18, the lower hooked ends of which are adapted to engage under the keepers or projections at opposite sides of the bottom section 1 of the lamp.

By placing the hooks 18 in engagement with the keepers on the bottom section of the lamp, and then rocking the forked lever by means of the combined hook and handle, the two sections of the lamp are drawn tightly together and rigidly held, after which the

hook on the crown of the lever may be inserted in the rim of the hat or helmet.

An emergency oil burner 19 is inserted in a compartment especially provided therefor in the top section of the lamp, said pocket being water-proof, so as to exclude the water contained in the upper chamber of the top section. This emergency lamp is adapted to be filled with oil, and embodies a wick 10 20, a filling cap 21, and a hook 22 adapting said emergency burner to be applied to the miner's hat, while he is engaged in refilling or recharging the acetylene lamp. The emergency burner is wholly contained within 15 in the plane of the top section of the lamp, and does not interfere with the use thereof in any way.

23 designates a gasket forming a tight joint between the upper and lower sections 20 of the lamp.

The plug 14 and the cap 21 are attached

to the body of the lamp by links 24 and 25, respectively.

What is claimed is:

A miner's gas lamp, comprising separable 25 top and bottom sections, and a combined support and fastener for securing the top and bottom sections together, embodying a forked lever straddling the top section and pivotally attached thereto, a supporting 30 hook projecting from the crown of the fork, coupling hooks pivotally connected to the side arms of the forked lever, and projections on the bottom section engaged by said coupling hooks. 35

In testimony whereof I affix my signature in presence of two witnesses.

WOLFGANG GSCHWENDNER.
